DESIGN FOR A POCKET FLASHLIGHT OR LIKE ARTICLE

Peter Copeland, New York, N. Y., assignor to Sidney Schwartz, New York, N. Y.

Application October 29, 1945, Serial No. 123,262

Term of patent 14 years

(Cl. D48—24)

To all whom it may concern:

Be it known that Peter Copeland, a citizen of the United States and resident of New York, in the county of New York and State of New York, has invented a new, original, and ornamental Design for Pocket Flashlight or Like Article, of which the following is a specification, reference being had to the accompanying drawing, forming part thereof, in which Figs. 1 and 2 are side elevational and top plan views, respectively, of a pocket flashlight or like article, showing my new design. Figs. 3 and 4 and 5 are rear, front and bottom views, respectively, thereof.

I claim:

The ornamental design for a pocket flashlight or like article, as shown.

PETER COPELAND.
